MATERIAL SEPARATOR

Francis H. Clute, Rocky Ford, Colo., assignor to The Clute Corporation, Rocky Ford, Colo., a corporation of Colorado

Application April 2, 1956, Serial No. 575,461

12 Claims. (Cl. 209—144)

This invention relates to a mineral or seed separator, and primarily to ore sorting apparatus for separating comminuted or pulverized metalliferous material from its gangue through employment of artificial currents of air directed through a novel separator and a collector for the lighter particles that are separated from the material by the action of combined cyclonic and straight air flow through the said separator.

It is the primary object of the instant invention to provide a mineral separator employing opposed, substantially semi-conical air flow passages alongside a primary passage for free vertical flow of air to create cyclonic air movements that operate to draw lighter particles spirally inward toward the center of such semi-conical passages from the primary portion and permit heavier particles to return by gravitation to the inlet of the separator.

The most important object of the present invention consists in the provision of a separator for comminuted material that recognizes the phenomenon of cyclonic air movements in the northern hemisphere which is clockwise, and wherein air moves spirally inward toward the center of the cyclone for the purpose of drawing lighter particles outwardly in opposite directions from the center of the separator and force the same into a collector that communicates with the outlet of the separator at the uppermost end of the latter.

Another important object of the present invention is to provide separating apparatus for comminuted material having particles of different specific gravities and adapted to handle material wherein the mineral is heavier than its gangue as efficiently as the apparatus handles material having a mineral that is lighter than its gangue.

Mineral separators employing a straight flow of air have heretofore been suggested and employed, but for the most part the same are only approximately 50% efficient and when the same operate on a forced draft principle, an extremely dusty condition is presented. Furthermore, those heretofore employed which operate on a suction principle as in the instant invention, are incapable of preventing a substantial flow of the lighter particles beyond a point of collection.

In accordance with the principles of the instant invention, separation is confined within an upright tube or body and through use of suction the fine particles are separated from a straight flow of air by a pair of opposed cyclonic air movements which are created on opposite sides of such straight air flow. The two cyclonic motions create a suction that operates to pull the light particles out of the straight flow of air, thereby permitting the heavier particles to drop out of the separator tube. The light particles are thereupon conveyed to a collector within which they are dropped and not permitted to pass out of the collector through the air discharge tube which communicates with the collector.

A dead air space is provided in surrounding relationship to the air outlet tube to prevent passage of even fine dust to the suction fan. Furthermore, the collector itself

2

is in the form of a pair of relatively telescoped cones to deaden the suction within the collector and permit feeding of the lighter particles from the lowermost end of the collector.

5 Reference may be had to the accompanying drawings and following specification for a more detailed explanation of the material separator and in the drawings:

Figure 1 is a side-elevational view of a mineral separator made pursuant to my present invention, parts being broken away for clearness;

Fig. 2 is a transverse cross-sectional view taken on line II—II of Fig. 1;

Fig. 3 is a transverse cross-sectional view taken on line III—III of Fig. 1;

Fig. 4 is a front-elevational view of the mineral separator; and

Figs. 5, 6, 7 and 8 are transverse cross-sectional views taken on corresponding section lines illustrated in Fig. 4 of the drawings.

15 The structure shown in Fig. 1 of the drawings includes four essential components, namely, a separator 10, a collector 14, air passage means 16, and a conventional separating device 18, the latter of which may well be quite conventional in that the same employs a plurality of sizing screens for initial separation of mineral from its gangue.

The separator 10 is in the nature of an elongated upright body or tube that includes a pair of flat, spaced-apart, side walls 20 and 22, both of which progressively decrease in widths as the uppermost ends thereof are approached. The side walls 20 and 22 also converge relatively as the lowermost ends thereof are approached as is evident in Figs. 5 to 7, inclusive. Separator 10 includes a lowermost portion 24 that may be of uniform width, 30 height and thickness and of substantially rectangular contour as shown in Fig. 8. The lowermost end of the portion 24 is open to present a first inlet and an elongated slot 26 in one side of the portion 24 adjacent the upper end of the latter presents a second inlet. It can be seen, therefore, that the distance between the walls 20 and 22 and their widths at the lowermost ends of walls 20 and 22 correspond with the width and thickness of the lower portion 24 and form a continuation thereof.

35 The side walls 20 and 22 are interconnected by end walls 28 and 30 that progressively increase in width as the uppermost ends thereof are approached as seen in Figs. 5, 6 and 7 and as is apparent in Fig. 1 of the drawings. Consequently, the separator 10 progressively decreases in width between the portion 24 and the upper ends of the side walls 20—22 and end walls 28—30, and progressively increases in thickness or horizontal depth as the uppermost end thereof is approached.

40 Side walls 20 and 22 are provided with outwardly bulged, substantially semi-conical portions 32 and 34, respectively, extending throughout the lengths thereof and progressively increasing in diameter as the uppermost ends thereof are approached as again seen best in Figs. 5—7. The semi-conical portions 32 and 34 merge 45 at the upper ends thereof and diverge relatively as the inlet slot 26 is approached. There is presented, therefore, a central primary passage 36 for free straight vertical flow of air in the separator 10 from separator portion 24 to the upper end of the separator 10 and a pair 50 of opposed secondary air passages 38 and 40, one on each side of the primary passage 36 and communicating therewith. Attention is specifically called to the fact that, at this point, the passages 38 and 40 are in opposed relationship with respect to a vertical plane intersecting the primary passage 36 in parallelism to the walls 20 and 22 for proper pulling action of cyclonic currents of

air created within passages 38 and 40 as will hereinafter be made clear.

The passages 36, 38 and 40 all communicate with a single collecting plenum 42 forming the upper end of the separator 10 and extended into a lateral branch 44 which communicates tangentially with the collector 14 as best seen in Fig. 2 of the drawings.

The collector 14 is in the nature of a pair of cones 46 and 48 which are relatively telescoped, the lowermost end of the cone 46 extending into the uppermost end of cone 48 as illustrated in Fig. 1. The upper end of the cone 46 is provided with a cylindrical portion 50 and it is with such portion 50 that the laterally extending branch 44 of plenum 42 extends.

The air passage 16 includes a discharge tube 52 that extends into the upper end of the cylindrical portion 50 and communicates with a suction fan (not shown). More specifically, the discharge tube 52 extends into a pipe 54 that is closed at the upper end thereof and extends through the top wall of cylindrical portion 50, presenting a dead air space 56 surrounding the tube 52.

The cone 48 terminates at the lowermost end thereof in a cylindrical spout 58 normally closed by a weighted, hinged door 60 that automatically releases the material in a continuous feed in direct ratio to the input into collector 14.

The coarse or rough separator 18 is associated with the separator 10 adjacent the portion 24 of the latter in the manner shown by Fig. 1 so that its screenings may either be fed into the air stream at the lowermost open end of the rectangular portion 24, or through inlet slot 26. It is noted that screen separator 18 is provided with a terminus 62 extending beneath the lower end of the rectangular portion 24 and with spout means 64 communicating with the inlet slot 26.

The inlet slot 26 is employed whenever the comminuted material contains minerals that are heavier than the gangue to be removed therefrom, as in the case of tungsten, gold and the like, and whenever the separator is used for that purpose the relatively heavy mineral gravitates from the separator 10 through the lowermost open end of the portion 24 thereof whereas the gangue is carried upwardly and deposited in the collector 14.

However, when the mineral to be separated is lighter than its gangue, as in the case of mica, the comminuted materials are fed to the air stream at the lowermost open end of the portion 24 of separator 10. In that instance, the mica is deposited in the collector 14 whereas the heavier gangue is discharged through the lowermost open end of collector 10. However, it has also been found that lighter minerals such as mica may also be satisfactorily separated by feeding the same through inlet slot 26.

In either event, the material initially moves upwardly within the passage 36 of collector 10 and by virtue of the cyclonic movement of the air in the passages 38 and 40 the lighter particles are drawn laterally into the passages 38 and 40 from the passage 36. This action takes place by virtue of the natural tendency of the spirally-whirling air to move inwardly toward the center of the passages 38 and 40. The heavier particles, however, within the passage 36 between side walls 20 and 22 gravitate back to the lowermost inlet end of the portion 24 of collector 10.

The light particles that are removed from the passage 36 are conveyed upwardly through the passages 38 and 40 into the plenum 42 and are discharged spirally into the cylindrical portion 50 of collector 14 by virtue of tangential relationship of the lateral branch 44 to the collector 14.

The provision of dead air space 56 surrounding the discharge pipe 52 prevents even the finest dusty material from passing outwardly through the air passage 16 to the suction fan by virtue of the fact that the particles

entering the cylinder 50 strike the pipe 54 and are projected back into the spiral air stream.

The provision of cone 48 surrounding the lowermost foremost end of cone 46 deadens the suction within collector 14 and thereby permits discharging the collected particles from the collector 14 upon opening of door 60.

It has been found that separations will be made where in there is virtually no more than one-tenth of one percent difference in specific gravity. When the mineral to be separated is free from its gangue it is possible to obtain concentrates up to a grade of 99-plus percent, and when the mineral that is to be separated is attached to the gangue the grade of the ore can be raised from 40% to 90%.

15 The efficiency of the separator is evident by the fact that even in the case of mica wherein the mineral is substantially the same weight at its gangue, a high concentrate of mineral can be separated. The efficiency of the machine, of course, is dependent upon the separation of the mineral from its gangue, all of which must be performed in the usual manner by regrinding, smelting or other processing. In other words, if the mineral readily separates from its gangue, the resultant concentrate is relatively free of foreign material through use of the mineral separator just above described.

20 While the above description of the separator forming the subject matter of the instant invention has been discussed primarily in connection with the sorting of ore, it is now readily apparent that the same is readily adaptable for use in separating virtually any materials that might be co-mingled and have different specific gravities. For instance, the separator has been used successfully in the separation of wheat from barley, dodder from alfalfa and shells from pecan meats. Through use of the separator 25 additionally, the germination of beet, zinnia, cantaloupe and watermelon seeds has been raised from 50% to 99%. Accordingly, it is seen that through use of the above-described invention a wide range of materials may be successfully separated.

40 Having thus described the invention, what is claimed as new and desired to be secured by Letters Patent is:

1. Separating apparatus for comminuted material having particles of different specific gravities comprising an upright body having an inlet, and an outlet spaced above the inlet, said body being hollow for flow of artificial currents of air from the inlet to the outlet, there being a pair of opposed, substantially semi-conical portions forming a part of said body and progressively decreasing in diameter as said inlet is approached for cyclonic flow of said air, and a central portion communicating with the semi-conical portions therebetween for free vertical flow of said air, whereby lighter particles are drawn from the central portion into the semi-conical portions and carried to said outlet, and heavier particles return by gravity within the central portion to the inlet when the material is introduced into the air stream at said inlet.

2. Separating apparatus for comminuted material having particles of different specific gravities comprising an upright body having an inlet, and an outlet spaced above

45 the inlet, said body being hollow for flow of artificial currents of air from the inlet to the outlet, there being a pair of opposed, substantially semi-conical portions forming a part of said body, said semi-conical portions diverging and

50 progressively decreasing in diameter as said inlet is ap-

proached for cyclonic flow of said air, and a central portion

55 communicating with the semi-conical portions there-

between for free vertical flow of said air, whereby lighter

60 particles are drawn from the central portion into the semi-

65 conical portions and carried to said outlet, and heavier

70 particles return by gravity within the central portion to the

75 inlet when the material is introduced into the air stream at said inlet.

3. Separating apparatus for comminuted material having particles of different specific gravities comprising an upright body having an inlet, and an outlet spaced above

the inlet, said body being hollow for flow of artificial currents of air from the inlet to the outlet, there being a pair of opposed, substantially semi-conical portions forming a part of said body and progressively decreasing in diameter as said inlet is approached for cyclonic flow of said air, said semi-conical portions being disposed on opposite sides of a central vertical plane through the body, and a central portion communicating with the semi-conical portions therebetween for free vertical flow of said air, whereby lighter particles are drawn from the central portion into the semi-conical portions and carried to said outlet, and heavier particles return by gravity within the central portion to the inlet when the material is introduced into the air stream at said inlet.

4. Separating apparatus for comminuted material having particles of different specific gravities comprising an elongated upright body having an inlet, and an outlet spaced above the inlet, said body being hollow for flow of artificial currents of air from the inlet to the outlet, the transverse, cross-sectional contour of the body being substantially rectangular at the inlet, there being a pair of opposed, substantially semi-conical portions forming a part of said body and progressively decreasing in diameter as said inlet is approached for cyclonic flow of said air, and a central portion communicating with the semi-conical portions therebetween for free vertical flow of said air, whereby lighter particles are drawn from the central portion into the semi-conical portions and carried to said outlet and heavier particles return by gravity within the central portion to the inlet when the material is introduced into the air stream at said inlet.

5. Separating apparatus for comminuted material having particles of different specific gravities comprising an elongated upright body having an inlet, and an outlet spaced above the inlet, said body being hollow for flow of artificial currents of air from the inlet to the outlet, the transverse, cross-sectional contour of the body being substantially rectangular at the inlet, with the thickness thereof appreciably less than the width thereof, there being a pair of opposed, substantially semi-conical portions forming a part of said body and progressively decreasing in diameter as said inlet is approached for cyclonic flow of said air, and a central portion communicating with the semi-conical portions therebetween for free vertical flow of said air, whereby lighter particles are drawn from the central portion into the semi-conical portions and carried to said outlet and heavier particles return by gravity within the central portion to the inlet when the material is introduced into the air stream at said inlet.

6. Separating apparatus for comminuted material having particles of different specific gravities comprising an elongated upright body having an inlet, and an outlet spaced above the inlet, said body being hollow for flow of artificial currents of air from the inlet to the outlet, the transverse, cross-sectional contour of the body being substantially rectangular at the inlet, with the thickness thereof appreciably less than the width thereof, there being a pair of opposed, substantially semi-conical portions forming a part of said body and progressively decreasing in diameter as said inlet is approached for cyclonic flow of said air, the body progressively decreasing in thickness as the inlet is approached, and a central portion communicating with the semi-conical portions therebetween for free vertical flow of said air, whereby lighter particles are drawn from the central portion into the semi-conical portions and carried to said outlet and heavier particles return by gravity within the central portion to the inlet when the material is introduced into the air stream at said inlet.

7. Separating apparatus for comminuted material having particles of different specific gravities comprising an elongated upright body having an inlet, and an outlet spaced above the inlet, said body being hollow for flow of artificial currents of air from the inlet to the outlet, the transverse, cross-sectional contour of the body be-

ing substantially rectangular at the inlet, with the thickness thereof appreciably less than the width thereof, the body progressively increasing in width as the inlet is approached, there being a pair of opposed, substantially semi-conical portions forming a part of said body and progressively decreasing in diameter as said inlet is approached for cyclonic flow of said air, and a central portion communicating with the semi-conical portions therebetween for free vertical flow of said air, whereby lighter particles are drawn from the central portion into the semi-conical portions and carried to said outlet, and heavier particles return by gravity within the central portion to the inlet when the material is introduced into the air stream at said inlet.

15 8. Separating apparatus for comminuted material having particles of different specific gravities comprising an elongated upright body having an inlet, and an outlet spaced above the inlet, said body being hollow for flow of artificial currents of air from the inlet to the outlet, the transverse, cross-sectional contour of the body being substantially rectangular at the inlet, with the thickness thereof appreciably less than the width thereof, the body progressively increasing in width and progressively decreasing in thickness as the inlet is approached, there being a pair of opposed, substantially semi-conical portions forming a part of said body and progressively decreasing in diameter as said inlet is approached for cyclonic flow of said air, and a central portion communicating with the semi-conical portions therebetween for free vertical flow of said air, whereby lighter particles are drawn from the central portion into the semi-conical portions and carried to said outlet, and heavier particles return by gravity within the central portion to the inlet when the material is introduced into the air stream at said inlet.

35 9. Separating apparatus for comminuted material having particles of different specific gravities comprising an elongated, upright, hollow body having a pair of spaced, flat, interconnected side walls, each progressively decreasing in width as the uppermost ends thereof are approached and diverging relatively as said uppermost ends thereof are approached, each side wall being provided with an arcuate, outwardly bulged, substantially semi-conical portion along one upright edge thereof progressively increasing in diameter and converging relatively as said uppermost ends of the side walls are approached, said body having an inlet, and an outlet spaced above the inlet for free vertical flow of artificial currents of air between said side walls from the inlet to the outlet, and for cyclonic flow of said air within said portions, whereby lighter particles are drawn from between said side walls into said portions and carried to said outlet, and heavier particles return by gravity between said side walls to the inlet when the material is introduced into the air stream at said inlet.

55 10. Separating apparatus for comminuted material having particles of different specific gravities comprising in combination, a hollow collector having an air discharge tube thereinto through the uppermost end thereof; and an elongated, upright, hollow body having a pair of spaced, flat, interconnected side walls, each progressively decreasing in width as the uppermost ends thereof are approached and diverging relatively as said uppermost ends thereof are approached, each side wall being provided with an arcuate, outwardly bulged, substantially semi-conical portion along one upright edge thereof progressively increasing in diameter and converging relatively as said uppermost ends of the side walls are approached, said body having an inlet, and an outlet spaced above the inlet and communicating tangentially with said collector for free vertical flow of artificial currents of air between said side walls from the inlet to the outlet, and for cyclonic flow of said air within said portions, whereby lighter particles are drawn from between said side walls into said portions and carried through said

outlet to the collector and heavier particles return by gravity between said side walls to the inlet when the material is introduced into the air stream at said inlet.

11. Separating apparatus as set forth in claim 10 wherein said collector is provided with an open bottom pipe surrounding the tube within the collector for creating a dead air space between the tube and the pipe to prevent passage of said lighter particles through the tube.

12. Separating apparatus as set forth in claim 10 wherein said collector is provided with a pair of superimposed cones, the lowermost end of the upper cone being partially telescoped into the uppermost end of the lower cone.
